UNITED STATES PATENT OFFICE.

JOHN THOMSON, OF NEW YORK, N. Y.

ELECTRIC FURNACE FOR REDUCING OXIDIZED ZINC CONCENTRATES BY CARBON.

1,321,683.

Specification of Letters Patent.

Patented Nov. 11, 1919.

Application filed January 27, 1919. Serial No. 273,234.

To all whom it may concern:

Be it known that I, JOHN THOMSON, a citizen of the United States, and a resident of the borough of Manhattan, county and State of New York, have invented new and useful Improvements in Electric Furnaces for Reducing Oxidized Zinc Concentrates by Carbon, of which the following is a specification.

10 This is an invention in electric furnaces for reducing oxidized zinc concentrates by carbon, according to the classical formula $ZnO + C = Zn + CO$, and the dominant objects thereof are to simplify and minimize 15 the cost of construction and maintenance and to substantially increase the efficiency over that of previous practice.

As herein employed, oxidized zinc concentrate (ZnO) may either be understood to 20 mean the usual mill-concentrate whose major ingredient is metallic, the remainder being gangue; or it may relate to igneously produced oxid of zinc whose recoverable metallic content may approximate the theoretical limit, about 80 percentum, the remainder being oxygen; and the reducing 25 agent, carbon, refers to granulated coal or coke containing a variable quantity of inert, residual matter. The object of the foregoing academic statement is to particularly accentuate the important correlative fact that if the charge to be reduced is composed of relatively low-grades of oxid and carbon the resulting residuum, usually in the form of 30 ash and sinter, will be a maximum, while if the charge were composed of balanced reacting volumes of pure oxid and pure carbon, there would then be no residual matter whatever.

40 The $ZnO + C$ reaction primarily becomes active at or about a temperature of 1,000° C.; but the rapidity thereof is a function of two factors: the quantitative supply of heat-units and the freedom with which the 45 evolved, vaporized products ($Zn + CO$) can escape from the charge-material. Thus, if the fume and gas are so confined as to produce "back-pressure" the intensity of the reaction may thereby be more or less diminished or even be wholly suspended. The sum of the pressure necessary to effect this mal-result is relatively quite nominal. Therefore, in these circumstances, if heat-units are being rapidly transferred and are

not with equal rapidity absorbed by the reaction, destructive "hot-spots" will be developed and energy is uselessly dissipated.

Again, when ZnO is highly heated it becomes a relatively effective conductor of electricity; and the failure to take cognizance of this phenomenon has hitherto been a potent cause of failure, as when a reactive charge has been placed in contact with a bed of carbon, serving as a resistor.

In the drawings, which depict a preferred practical realization of this invention and form a part of this specification:

Figure 1 is a vertical, transverse center section of the furnace, viewed as denoted by arrows A, A;

Fig. 2 is a vertical, longitudinal center section, according to arrows B, B;

Fig. 3 is a horizontal, sectional plan, along the plane indicated by arrows C, C;

Fig. 4 is a diagrammatic reproduction of Fig. 1 for the purpose of illustrating the thermacy of the operation.

The principal elements of the structure are as follows:

D is the brick-work which forms the base; 80 E, E', are the side-walls; F, F', are the end walls; H is the roof; I is the reaction chamber and J is a monolithic carbon resistor disposed along the longitudinal axis of the chamber, whose terminals, 5, 6, are connected to a source of energy, symbolically denoted by K.

The resistor is of the zig-zag type and comprises two parallel limbs 7, separated by a vertical space 8, except that their inner ends are joined by a connector, 9, whereby the electric circuit is in series. The said limbs are preferably formed from rectangular slabs, set edge-wise, vertically, resting on refractory supports within the chamber, 95 as 10, 12, 13.

As a unitary element, the resistor herein depicted is characterized by having its narrower sides beveled, 14, 15, whereby its current-density and corresponding heat-emissivity are greater along the faces and the bevels which are presented toward the object to be heated, or as is primarily shown in applicant's Patent No. 1,193,633 of August 8, 1916, particularly Figs. 5, 6 and 7 and claims 1, 2, 3 and 4 thereof.

In the present instance, another characteristic of the resistor which is of signal

importance consists in filling its slits and coating its surfaces with material or materials relatively non-conductive to electricity, immune to oxidization and non-reactive with carbon; also in usually curing the protective coating, by means of heat developed within the resistor itself, and carrying the temperature to a higher point than that at which it is eventually to be used, or as is set forth in applicant's pending application Serial No. 228,908, filed April 16, 1918.

The preferred material, or materials, referred to in the foregoing paragraph, is silicon carbide, or fused aluminum oxide, primarily combined with an element capable of being more or less fluxed at a relatively high temperature; and the said fluxing element should preferably be, in the present instance, of a silicious base, in that there will be more or less of physical contact with oxide of zinc.

The operative elements and the maneuver are as follows: The furnace-chamber is more or less filled with a reacting charge which surrounds the resistor, the material to be smelted being inserted through a relatively narrow longitudinal slot, 16. This opening is normally closed by a valve-plate, 30 L, preferably covered by charge-material, as denoted by the broken line 17, placed in a recess, M, on top of the furnace. The valve-plate has a rib, 18, whereby it may be conveniently engaged by a hooked-rod to be drawn or slid over, as to the position indicated by the dotted outline, 19, thereby opening the slot and permitting the superimposed material to flow into the chamber. In this wise, the hot inner surface of the valve-plate is not exposed to atmosphere; while the overlying concentrate serves to seal the roof-joints and is somewhat pre-heated.

The upper portion of the space between the limbs of the resistor is inclosed by a molded refractory, N, to be designated a deflector, resting upon shoulders, 20, 21 and is provided with a series of transverse ports, as 22.

50 In each side-wall, along the lower zone of the chamber, a series of extraction ports, 23, 24, are formed which are normally closed by free refractory plugs, as 25, and for their convenient insertion and removal handles, as 26, are provided.

The inner surface of the roof is upwardly beveled, as 27, 28, right and left toward the center, whereby to refract heat, received from the resistor, downwardly into the side-reaches of the chamber.

When the charge passes down through the roof-slot, it first impinges upon the deflector and runs off equally on either side.

In one of the end walls, near the top of 60 the chamber, is a molded throat, P, through

which the vaporized products of the reaction (Zn+CO) escape to a condenser, the latter not being shown; but a preferred design would be developed from that shown in the patent already cited together with 70 subsequent Patents Numbers 1,219,193 of March 13, 1917 and 1,265,937 of May 14, 1918.

Referring to Fig. 4, assuming that the chamber will have been filled as indicated 75 on the left hand side by the broken line 30, the upper bevels and the outer faces of the resistor will then be in physical contact with the charge; and while a portion thereof may sift through the openings, 22, 80 in the deflector, N, and thence down between the limbs of the resistor, there will yet be some unfilled space beneath its lower bevels. Heat will then be transferred to the charge by direct conduction, as denoted 85 by arrows a and the evolved fume and gas will flow through the comparatively shallow portion of the charge, with a minimum of restriction, as arrows b, c; from beneath the vaporized products will pass freely upwardly, as arrow d, and thence through the deflector ports, as arrows e, to condenser-throat, P.

When, however, the charge will have been partially reduced, as indicated on the right 95 hand side by the broken line 32, reactive heat will then be transferred by radiation as arrows h and m, and by heat from the upper bevels of the resistor refracted directly downwardly from the sloped roof, 100 as arrows n.

In the foregoing circumstances, the inner surfaces of the charge are the hottest, from whence the zinc-fume and monoxid of carbon pass off with the utmost freedom, 105 as and when evolved and with all the rapidity with which calories are supplied.

The fact has not been overlooked that the inert residuals of the reaction will accumulate upon the upper surface of the receding charge; but the final temperature, if the in-put of energy remains constant, will automatically rise to meet the additional obstruction.

After the zinc has been adequately exhausted, the extraction-ports 23 and 24 are opened when the residuum can be quickly withdrawn, as by means of rakes or hoes. During this operation, it is preferable to close the condenser-vent, or the fume-throat, 110 thereby avoiding the displacement of residual zinc-fume within the chamber and preventing what would be a deleterious circulation of air toward and through the condenser.

As stated at the outset of this specification, if a high-grade of roasted concentrate is used, especially if igneously produced, the reducing chamber may be successively charged in bulk; or the supply may be added 120

in increments intermittently; or the valve-plate may be removed for certain periods of time whereby charge-material would run in automatically to supplant the displacement at the rate of diminution caused by the reaction.

The thermal efficiency of this furnace is regarded as the highest that is possible to attain in the practice of the art for which it has been designed. For example, when the resistor is wholly immersed all of its heat flows into the charge except only that which passes to atmosphere from the terminals.

The "life" of the resistor, when formed and treated in the manner herein adverted to, is unknown; suffice it to say that its cost, as an element of up-keep, is probably as negligible a quantity as an incandescent carbon filament in an exhausted glass sphere.

It goes without saying that various modifications can readily be made in the depicted design as a whole, and also in its various elemental details, without evasion of the generic principles herein set forth in amplitude and summarized in the claims.

I claim:

1. An electric furnace for reducing oxidized zinc concentrates by carbon ($ZnO + C = Zn + CO$), comprising a zig-zag resistor the surfaces of which are relatively electrically non-conductive, immune to oxidation and nonreactive with carbon sustained centrally of the chamber of the furnace, said resistor being primarily enveloped by the charge to be reduced, and means for condensing the volatilized products of the reaction.

2. An electric furnace for reducing oxidized zinc concentrates by carbon ($ZnO + C = Zn + CO$) provided with a reaction chamber, the roof which is provided with a central, longitudinal charging slot, a zig-zag carbon resistor having spaced par-

allel limbs, and a deflector having a plurality of transverse ports sustained in the upper portion of the resistor space.

3. An electric furnace for reducing oxidized zinc concentrates by carbon ($ZnO + C = Zn + CO$) having a reaction chamber, a zig-zag carbon resistor sustained in said chamber and a plurality of extraction ports in the side-walls of the furnace, disposed along the lower horizontal zone of said chamber, through which the inert products of the reaction may be withdrawn.

4. An electric furnace for reducing oxidized zinc concentrates by carbon ($ZnO + C = Zn + CO$) having a reaction chamber, a zig-zag, carbon resistor, immune to superficial reactive attack sustained in said chamber whereby the heat is transferred to a reactive charge within the chamber by direct conduction, by radiation, and by refraction, substantially as hereinbefore set forth.

5. An electric furnace for reducing oxidized zinc concentrates by carbon ($ZnO + C = Zn + CO$) having a reaction chamber, a zig-zag, carbon resistor, having a plurality of limbs and sustained within said chamber a ported deflector within the chamber, and a fume-throat leading from the reaction chamber to a condenser, said parts being disposed so that portions of the volatilized products of reaction, when the furnace is charged, will escape upwardly from beneath the charge between the limbs of the resistor, through the ports of the deflector and finally to the said fume-throat.

This specification signed this 21st day of January, A. D., 1919.
